UNITED STATES PATENT OFFICE.

EBEN RAY PACKER, OF NEW ROCHELLE, NEW YORK, ASSIGNOR TO Q. & C. COMPANY,
OF NEW YORK, N. Y., A CORPORATION OF MAINE.

EMERGENCY KNUCKLE FOR CAR COUPLINGS.

Application filed March 5, 1921. Serial No. 449,712.

To all whom it may concern:

Be it known that I, EBEN RAY PACKER, a citizen of the United States, residing at New Rochelle, in the county of Westchester and State of New York, have invented new and useful Improvements in Emergency Knuckles for Car Couplings, of which the following is a specification.

This invention relates to emergency knuckles for car couplings and consists of an improved construction and arrangement thereof more fully to adapt it for universal use with the many standard types or makes of car couplings and which in addition possesses important features and advantages over the types of knuckles as heretofore employed particularly in the distribution of the metal to obtain a strengthened structure.

My improved emergency knuckle is particularly designed for use with the many standard types of railway car couplings which as is well understood are universally made in accordance with the M. C. B. standards but which vary considerably, particularly in the shapes and contours of the draw heads and therefore impose strict constructional limitations which must be complied with in the production of a practical emergency coupling. My improved knuckle is designed to conform to these standards and moreover is of an improved construction which meets the many other and important conditions of this particular art.

Important features of my present invention which contribute to successfully meeting the many requirements include the following: It is peculiarly formed to be interchangeable with the standard knuckles of the many types of car couplings now on the market so as to be adapted for replacing the regular knuckles when face worn or broken; it is adapted for effecting the locking of the parts where the usual locking parts are broken or defective; it is designed to be effective in coupling where one of the pin lugs of the draw head is broken off; it is adapted for effecting the coupling with normal spacing so as not to increase the distance between the cars thereby avoiding danger of injury to trainmen and permitting the proper connection of the air lines between cars; it is constructed so as to insure the successful automatic operation in coupling the cars and may be conveniently and readily installed so as to avoid delays to traffic.

Further important features of the emergency knuckle structure of my present invention consists of an improved design of an external holding lug type knuckle having the metal of the lug suitably arranged to engage with the outer side of the coupler head at the upper and lower marginal edges thereof which define the outer edges or ends of the upper and lower horizontal walls of the coupler head, whereby the horizontally applied pulling stresses will be resisted by the horizontal upper and lower walls of the coupler head in the direction edgewise of the metal so that maximum strength is obtained, and further in the provision of an internally acting retaining lug adapted to prevent excessive swinging or rotation of the knuckle inwardly of such dimensions as not to require removal of the locking parts to permit of its application.

The described and other important features and advantages of my present invention are illustrated in the accompanying drawings wherein like reference numerals are applied to the corresponding parts in the several views.

In the drawings:

Fig. 1 is a view in side elevation illustrating an approved embodiment of the features of my invention and showing my improved knuckle applied to a coupler head.

Fig. 2 is a plan view thereof showing the coupler head in horizontal section.

Fig. 3 is a perspective view of my improved knuckle as applied to the draw bar head.

As shown in the drawing my improved knuckle is illustrated as used to replace the ordinary knuckle of a standard type of railway car coupler. The body or supporting head 1 of the coupler as shown is of a standard modern type of draw bar head of hollow form, as illustrated, having its forward active surface of the usual contour conforming to the M. C. B. standards. As will be noted this type of coupler head is provided with the usual inclined jaw closing surface 2, superimposed pivot pin supporting lugs 3, 3 and is provided at its rear with a lateral wall or partition 4 of a form and size which would prohibit the use of an elongated holding arm of the jaw or knuckle 5 as heretofore customarily used.

The emergency knuckle 5 as here illustrated and in accordance with my invention

is formed with the locking jaw 8 of a contour conforming to the M. C. B. standards and is provided with a vertical aperture 9 therethrough to receive the usual pivot pin 10 of the coupling whereby it is held in position. To retain the locking jaw 8 of the emergency knuckle in locking or coupling position, an external holding lug 12 is formed integrally thereon and adapted to 10 engage the outer surface of the coupler head. The lug 12 is therefore operative to prevent swinging forwardly of the coupling jaw 8 and accordingly performs the function of the usual locking means in preventing releasing movement of the knuckle in the forward direction. It follows therefrom that in the event of the locking means of a coupler becoming broken the employment of this emergency knuckle will permit of obtaining an effective coupling with a jaw of ordinary type of a coacting coupling member. In automatic coupling under the described conditions it will be understood that the ordinary coupling knuckle of the coacting coupler will be the swinging or movable member and will be deflected inwardly by the surface 2 into the locking position in the usual manner.

To successfully so operate and to be positive in its automatic coupling operation it is required that the emergency coupling jaw 8 shall also be secured from rotation or swinging inwardly toward or into its supporting head 1. For this purpose I have provided the emergency knuckle element with a rearwardly extending arm portion 14 having its outer surface 15 suitably positioned to engage with the inner surface of the side wall 13 of the coupler head thereby 30 to act as a stop to prevent excessive movement inwardly of the jaw portion 8 whereby the latter cannot swing inwardly sufficient to prohibit the proper automatic coupling. The provision of both the external and internal engaging portions 12 and 14 of the knuckle will thus operate to secure the emergency knuckle in operative locked position at all times and the stops thus formed occupy but small space which permits of their being made with proper clearance to be interchangeable with the many types of coupler construction.

A particular and important feature resides in a special formation of the external lug 12 whereby it will engage the draw bar or coupler head in a manner whereby the pressures set up by the pulling stresses on the knuckle will be resisted by the horizontal top and bottom walls 16 and 17 of the coupler head and in consequence danger of dam-

age to the coupler head is reduced to the minimum. By this desirable arrangement there is produced a lug type of knuckle which does not apply the holding pressures to the more or less thin vertical wall 13 of the coupler head which is an objectionable feature of certain types of emergency knuckles hereinbefore used. For the purpose of avoiding this objection I have formed the lug 12 as best illustrated in Figs. 1 and 3, of suitably increased depth whereby the top and bottom marginal edge portions 18 thereof, will be positioned to engage the outer surface of the coupler head at the portions thereof defining or forming the outer edges of the upper and lower horizontal walls 16 and 17 of the coupler head. As a result the resistance to outward movement of the emergency knuckle will be opposed mainly by these horizontal walls and thereby by metal on edge or in compression offering the maximum resistance and correspondingly reducing or eliminating danger of damage to the draw bar head.

While I have described an approved embodiment of the features of my invention it will be understood that modifications may be made therein without departing from the scope of the invention as defined in the appended claims.

Having described my invention I claim:

1. An emergency knuckle adapted to take the place of the ordinary knuckle in a car coupling comprising a body provided with an aperture for receiving the pivot pin of the coupling, a coupling jaw and retaining means for retaining said jaw in locking position comprising an externally extended shoulder formed to engage the outer surface of the coupler or draw bar head to bear upon the portions thereof defining the ends or edges of the upper and lower horizontal walls of the head member, substantially as described.

2. An emergency knuckle adapted to take the place of the ordinary knuckle in a car coupling comprising a body provided with an aperture for receiving the pivot pin of the coupling, a coupling jaw and retaining means for retaining said jaw in locking position comprising an externally extended shoulder integrally formed on the jaw to engage the outer surface of the coupler or draw bar head and having its bearing portion engaging said surface within the plane of a horizontal wall of the coupler head, substantially as described.

In testimony whereof I have signed my name to this specification.

EBEN RAY PACKER.
